WARM AIR CIRCULATING AND FILTERING APPARATUS

Herman A. Phail, River Rouge, Mich.

Application September 16, 1932, Serial No. 633,500

2 Claims. (Cl. 230—128)

My invention relates to a new and useful improvement in a warm air circulating device adapted for use primarily on warm air heating systems and has for its object, the provision of a device wherein the circulating of air may be efficiently carried on.

Another object of the invention is the provision in a device of this class of a blower or fan housing so constructed and arranged that it may be easily and quickly assembled and disassembled.

Another object of the invention is the provision, in a device of this class having a blower or fan housing, of a plurality of baffle plates so that the air drawn to the housing may be drawn into the housing through various ports or openings, the baffle plates serving to equalize the suction transmitted to the various openings.

Other objects will appear hereinafter.

The invention consists in the combination and arrangement of parts hereinafter described and claimed.

The invention will be best understood by a reference to the accompanying drawing which form a part of this specification and in which,

Fig. 1 is a perspective view of a furnace embodying the invention.

Fig. 2 is a sectional view taken on line 2—2 of Fig. 1 and further indicated as to location by the section line 2—2 of Fig. 3.

Fig. 3 is a sectional view taken on line 3—3 of Fig. 2.

Fig. 4 is a perspective view of a baffle element used in the invention.

In the drawing I have illustrated the invention used as a warm air furnace having an air chamber 12'. In a plurality of the walls 12 of the furnace I provide openings 13 over which is placed a grid or covering 14.

In each of the openings I provide a purifying element consisting of a tubular frame 34 which is split on its inner sides and the inner ends 35 and 36 are extended parallel to provide a gripping portion between which may be gripped a suitable filtering element 37 formed from a wire mesh screen or the like. An absorbent layer 38, preferably formed from fabric, is secured in engagement with the filtering element 37 by means of the semi-circular clip 39 which is adapted to clip around the frame 34. This clip 39 carries the portion 40 which lies in engagement with the layer 38 which is provided with the teeth 41 punched therefrom adapted to penetrate the layer 38 and project into the filter element 37. When the layer 38 is saturated with a suitable anti-septic it serves as a germicidal agent for disin-

fecting the air passed therethrough. By having this layer 38 in a moist condition it assists the element 37 considerably in removing solid particles and lint from the air passed therethrough.

With this apparatus mounted in the inlet 5 openings of the wall in the furnace all of the air entering the furnace is purified by being freed from solid particles of foreign material and disinfected so that a sanitary condition is arrived at. I provide a housing having an inclined top 42 provided with the slotted openings 43 formed by the louvres 43' which are stationary. This top is provided with the inwardly turned portion 44 which is doubled upon itself as at 45 and angularly turned as at 46 to provide, in conjunction with the supporting bracket 47, a support for filter elements which may be positioned below the opening 43 and in the path of the incoming air.

This housing is provided at one corner with the vertically extending plate 48 having the inwardly projecting portion 49 lying parallel with the inwardly projecting portion 50 of a similar plate 48'. The inwardly projecting portion 50 is angularly turned to provide the portion 51 which projects inwardly toward and is in alignment with the portion 51' on the plate portion 49. A grid 52 is positioned between the shoulder forming portions 53 and 54 of the plates 48 and 48'. Each of these plates 48 and 48' is provided at one end with the inwardly projecting flange 55 engaged in a channel 56 formed in the plate 56' which corresponds in structure closely, to the structure of the plates 48 and 48'. On the plate 56' is the engagement portion 57 against which engages one side of the grid 58, the other side engaging the portion 63 on the plate 62 which is inwardly turned as at 61 to lie in alignment with the portion 60 turned inwardly from the plate 51. The plate 62 is angularly turned, as at 64, and bolted or otherwise suitably secured to the wall 65 of the furnace. The plates 51 and 62 serve to form, in conjunction with the connecting plates 161 and 162 a frame for reception of the filter elements positioned therein.

In the wall 65 is formed an opening 66 communicating with the warm air chamber 12' and through which a blast of air is directed by the blower or fan 67 driven by the electric motor 68. In ordinary heating installations this motor may, if desired, be controlled by a suitable thermostatic switch which has not been illustrated as the formation forms no part of the present invention and is of a construction which is well known. The inwardly turned portions 51 and 51' and 63 and 61 serve as supports for baffling 55

elements embodying oppositely disposed walls 69 and 70 having the ends doubled upon themselves to provide channels 71 and 72 which may slip over the inwardly turned portions 51 and 51' as shown in Fig. 3. Positioned between these plates 69 and inclined to the vertical are the baffle plates 73 which rest upon the supporting members 74 and 75 and are provided with the flange 76. As shown in Fig. 3 these baffle plates taper toward their inward ends and the purpose of this arrangement is that the air drawn into the housing by the blower or fan may be equalized for the various inlet openings. Experience has shown that unless the baffle plates are arranged, mounted, and constructed in this manner, a greater volume of air will be drawn inwardly of the housing from one side than from the other. But, since the area of these sides is substantially the same and since it is desirable that all of the filter elements be called upon to function while the blower is operating, it is quite important that uniform distribution of air entry at the various opening sides of the housing be effected. To this end the arrangement and formation of the baffles is especially directed.

The plates 56' and 48 are secured together by suitable bolts 164 as are likewise the crossing plates at the opposite corners. It is believed obvious from the description given that the device may be shipped in a knocked down condition and the various parts readily and quickly assembled into the position. In operation when the blower or fan construction is mounted, the device will function in the usual manner as a natural draft system when the fan is not operated.

The simplicity of the device is believed evident from the description given and it affords a com-

pact structure in which the various round cold air ducts, and round warm air pipes in a warm air heating system may be eliminated.

While I have illustrated and described the preferred form of my invention I do not wish to limit myself to the precise details of structure shown but desire to avail myself of such variations and modifications as may come within the scope of the appended claims.

Having thus described my invention, what I claim as new and desire to secure by Letters Patent is:

1. In a device of the class described, a blower or fan housing comprising corner supporting members; inwardly projecting flanges on each of said supporting members; a pair of side walls; a baffle plate carried by and positioned between said side walls; and a channel carried by each of said side walls slidably over said flanges for retaining said baffle plates projecting inwardly from one of said openings.

2. In a device of the class described a housing having plurality of inlet openings on different sides thereof, an upstanding inwardly directed flange at opposite sides of each of said openings; a baffle construction comprising a pair of oppositely disposed walls spaced apart and converging relatively to each other, the ends of said walls at the divergent ends being doubled upon themselves and embrace the flanges at opposite sides of an opening; a plurality of spaced supporting bars on the inner surface of each of said walls inclined to the horizontal, corresponding bars on opposite walls being in alignment; and a baffle plate positioned on each pair of corresponding bars.
